United States Patent Office

Des. 220,310
Patented Mar. 30, 1971

220,310

WIRE REEL

James J. Smith, 502 N. Puget St.,
Olympia, Wash. 98501

Filed Dec. 3, 1969, Ser. No. 20,345

Term of patent 14 years

Int. Cl. D8—03

U.S. Cl. D8—220

FIG. 1

FIG. 2

FIG. 1 is a left front perspective view of the wire reel embodying my new design;

FIG. 2 is a side elevational view with apparatus collapsed.

I claim:

The ornamental design for a wire reel, substantially as shown.
